[57] CLAIM

The ornamental design for a remote controller for scale, as shown and described.

DESCRIPTION

FIG. 1 is a top plan view of the remote controller for scale showing our new design;

FIG. 2 is a bottom plan view;

FIG. 3 is a front elevational view;

FIG. 4 is a rear elevational view;

FIG. 5 is a right side elevational view; and

FIG. 6 is a left side elevational view thereof.
